UNITED STATES PATENT OFFICE.

MILTON L. DODGE, OF NEWBURYPORT, MASSACHUSETTS.

METHOD OF AND MACHINE FOR ATTACHING COUNTERS TO TURN SHOES.

Application filed December 10, 1923. Serial No. 679,550.

This invention relates to a method of and machine for attaching previously molded counters in turn shoes after the lasts have been removed and the shoes turned which 5 will insure the close engagement of the upper to the counter and to the marginal portion of the sole at and immediately forward of the heel seat.

One of the great advantages of fastening 10 the counter after the heel of the shoe is turned is that the heel portion of the upper may be employed to properly position the counter so that the upper is drawn there-over smooth and tight. The counter having 15 been then attached the lining is turned within the counter and made fast in any suitable way. While various means of attaching the counter may be employed, I have found that a stapling machine may be utilized to good 20 advantage particularly when the counter and shank piece have been attached together prior to assembling them in the shoe, the stapling machine being provided with some additional parts especially designed for the purpose. 25 Not only may the fastening of the counter be done by this machine, but the counter and sole may be so formed by the clamping members which hold the shoe and counter assembled for the fastening operation that the 30 upper is made to closely engage the sole adjacent to its margin.

For a more complete understanding of this invention reference may be had to the accompanying drawings in which

35 Figure 1 is a side elevation of a stapling machine having parts especially designed for attaching counters.

Figure 2 is an inverted plan of the upper pressure plate or die.

40 Figure 3 is a section on line 3—3 of Figure 2.

Figure 4 is a perspective of the lower pressure plate or die.

45 Figures 5 and 6 are detail sections through the presser plate in operative relation to a shoe laterally and longitudinally of the shoe, respectively.

Figures 7 and 8 are plan and side elevations, respectively, showing a modified form 50 of upper presser member.

Figure 9 is a perspective of a spring element used in this construction.

Figure 10 is a perspective illustrating a further modification.

55 Referring first to Figure 1, at 1 is indicated a machine standard supporting at its

top staple forming and driving mechanism in a machine head indicated generally at 2. This may be of any usual type and consequently will not be described in detail. The 60 staples are driven through a nose 3 depending from the head 2 forwardly of the standard 1 in the usual manner. At 4 is shown a bracket extending forwardly from the pedestal or standard 1 and this bracket may be 65 utilized to support parts specially designed for the counter-attaching operation. To this bracket is made fast a forwardly extending arm 5 having a vertically perforated sleeve 6 at its forward end. In this sleeve a 70 plunger 7 is vertically slidable and this plunger carries at its upper end a presser member or form 8, shown detached in Figure 4, and which forms a support for the shoe as will hereinafter appear. This form 75 8 may be moved upwardly toward the nozzle 3 or lowered therefrom by the operator and for this purpose a cable or chain 9 is shown as passing about a pulley 10 journaled 80 on the arm 5 and having one end made fast 85 as at 11 to the lower end of the plunger and its other end made fast as at 12 to a treadle 13 fulcrumed at 14 at the lower end of the standard 1. Cooperating with the form 8 is an upper presser member 15 shown detached 90 in Figures 2 and 3. This presser member has a central conical opening 16 into which the nozzle 3 is adapted to extend as shown more particularly in Figure 6.

In order that the member 15 may be fixed 95 firmly to the nozzle it may be formed with the slot 17 (see Figure 2) extending inwardly from its forward face to the perforation 16 and passing somewhat rearwardly thereof so as to form a pair of spring jaws 18 which 100 may be brought together to clamp the nozzle 3 in position in the opening 16, as by means of a screw 19 threaded in one of these jaws and having a head 20 bearing in a socket in the other jaw. The shoe to which the counter is to be attached is prepared for this 105 operation by pulling the last and turning, the lining at the heel portion extending outwardly of the shoe as shown in dotted lines in Figure 1 at 25. A previously molded counter 26 to which a filling piece 27 has been applied is then placed over the lower presser member or form 8, and the shoe in inverted position, as shown in Figure 1, is 110 then placed thereover and pulled forwardly so that the counter is seated firmly against the heel end of the upper, this being done

when the plunger 7 is in its lowered position. If desired the counter filling may be placed in position in the shoe and then both inverted over the form. By pressure exerted on the treadle 13 the assembled parts are then raised into co-operative relation to the upper presser member 15 so that this member engages the exposed heel end face of the sole and the staple is then driven through the stapling machine nozzle and the sole of the shoe and the filling piece and clinched on the support 8 thus fastening the parts in position.

In order, however, that the counter may retain the shoe upper closely adjacent the edge of the sole about the heel seat and the shank portion of the shoe, the presser member 8 and 15 may be formed, as shown in Figures 2, 3 and 4, with a marginal upstanding rib or bead 30 partially surrounding a central depressed portion 31, while the member 15 has an outwardly beveled or flaring depending rib 35 formed to embrace the rib 30 as the presser members are brought together, the ribs 35 and 30 engaging the upper and counter between them centering the counter and shoe relative to each other and forming the marginal portions of the counter into an outwardly extending bead pressing closely toward the marginal portions of the sole outwardly of the stitch line 40 between the sole and upper so that the parts are firmly urged together about the margin of the heel seat and shank portions, this being done when the parts are being clamped together preparatory to the fastener driving operation. This action is further facilitated if the counter is previously formed with an outwardly extending bead as disclosed in my Patent No. 1,430,158, dated September 26, 1922. After the fastening has been driven, the treadle 13 is allowed to rise and the shoe is removed from the lower block 8. The lining 25 is then turned and tucked inwardly to cover the inner face of the counter and it is attached in position in any suitable or usual manner.

It is thus seen that the heel portion of the upper as well as the presser member 15 is employed to properly position the counter and shank piece with relation to the sole so that a smooth close fit of the upper about the counter is insured, and that by means of the formation of the cooperating presser members a close joint between the upper and the sole edge is effected.

The filling piece may, if desired, be prolonged forwardly of the counter thus serving also as a shank piece as shown.

If desired also the upper presser member may be so formed as to wipe down the upper over the counter as the shoe is moved into position for the staple to be driven. For this purpose the constructions shown in Figures 7 and 10 have been devised. Refer-

ring to the form shown in Figures 7 to 9, the presser block is indicated at 50 and is made quite similar to the presser member 15, except that it has attached thereto at opposite sides resilient wiper plates 51 and 70 at its rear end a similar plate 52 made of spring metal. One of these plates is shown detached in Figure 9. These plates extend below the lower face of the presser member 50 and act to wipe the upper down 75 closely against the outer face of the counter as the shoe is moved upwardly by means of the treadle until the presser member 50 clamps the sole against the counter.

In place of these resilient strips the upper presser member may be formed sectional as shown in Figure 10. Referring to this figure, the presser member comprises side sections 55 and a central section 56. The side sections are urged toward the central 85 section by means of springs 57 surrounding adjusting bolts 58 threaded into the section 56 and passing through guide openings in the side sections, the springs bearing between the heads of these bolts and the outer 90 faces of the sections 55. By this means the lower edge portions 59 of the side sections are caused to resiliently engage the sides of the upper and wipe the upper down about the counter until the presser member is 95 firmly seated against the shoe sole. The central member 56 has an opening 60 therethrough for the reception of the nose of the stapling machine to which it may be fixed by means such as a set screw 61 threaded 100 in the section 56, one of the side sections 55 being provided with an opening 62 opposite the head of the set screw through which access may be had thereto so that the screw may be tightened or loosened as may be 105 desired.

While a stapling machine has been herein illustrated, it is, of course, evident that any other suitable fastener inserting machine might be substituted therefor.

Having thus described an embodiment of this invention it should be evident to those skilled in the art that various changes and modifications may be made therein without departing from its spirit or scope as defined 115 by the appended claims.

I claim:

1. The method which comprises inserting a molded counter within the upper of a turned shoe, seating the counter firmly 120 against the heel portion of the upper, pressing the marginal heel seat portion of the counter against the upper and the marginal heel seat portion of the sole, and while the parts are so held pressed fixing the counter 125 in position.

2. The method which comprises inserting a molded counter within the upper of a turned shoe, seating the counter firmly against the heel portion of the upper, press- 130

ing an outwardly extending bead about the heel seat portion of the counter in position to hold the upper closely against the heel seat outwardly of the stitch line, and fixing 5 the counter in position.

3. The method which comprises inserting a previously assembled molded counter and filling piece within the upper of a turned shoe, seating the counter firmly against the 10 heel seat portion of the upper, pressing an outwardly extending bead about the heel seat portion of the counter, clamping the upper to the sole margin outwardly of the stitch line between the sole and upper, and 15 then driving a fastener through the sole and filling piece to retain the parts assembled.

4. The method which comprises inserting a previously assembled molded counter and filling piece within the upper of a turned 20 shoe, seating the counter firmly against the heel seat portion of the upper, pressing an outwardly extending bead about the heel seat portion of the counter, clamping the upper to the sole margin outwardly of the 25 stitch line between the sole and upper, then driving a fastener through the sole and filling piece to retain the parts assembled, releasing the shoe, and inserting the lining at the heel end of the shoe within the counter.

30 5. The method which comprises placing a previously assembled molded counter and filling piece over a form having a marginal rib engageable therewith outwardly of the stitch line between the sole and upper of a 35 shoe in which the counter and filling piece are to be incorporated, placing the turned heel portion of the shoe in inverted position over the counter and filling piece, the lining of the shoe being unattached to the 40 sole and pulled outwardly therefrom, pressing on the exposed heel end face of the sole toward said form, driving a fastener from said exposed heel end face through the sole and filling piece and clinching the fastener 45 on said form, releasing the shoe, and tucking the unattached lining within the counter and securing it in position.

6. The method which comprises assembling 50 a counter within the turned heel portion of a shoe off the last, wiping the heel portion of the upper about the counter, and fixing the counter in position.

7. The method which comprises inserting a previously assembled counter and filling 55 piece in the heel portion of a turned shoe off the last, wiping the heel portion of the upper over the counter, and driving a fastener through the sole and filling piece to fix the parts in position.

60 8. In a machine for attaching counters, a

support shaped to receive a molded counter inserted within the upper of a shoe and having an upwardly extending marginal bead engaging the sides and rear of the sole-engaging portion of the counter, a member 65 relatively movable to engage the free end face of the sole and having a downwardly extending margin engageable outwardly of the shoe upper and clamping the upper and counter against said bead, and means actuatable to fasten the counter in position while the shoe is held between said support and member.

9. The combination with a form over 70 which a molded counter and the heel portion of a shoe in assembled relation thereto may be placed, of a presser member engageable with the heel end face of the shoe for clamping the counter to the shoe, said member having portions acting resiliently to 80 wipe the upper over the counter as it is being brought into clamping position.

10. The combination with a form over 85 which a molded counter and the heel portion of a shoe in assembled relation thereto may be placed, said form having a marginal bead engageable with the counter outwardly of the stitch line between the sole and upper of the shoe, of a presser member engageable with the exposed heel end face of the shoe, 90 and spring elements positioned to wipe the upper over the counter as said member is being moved to clamping position.

11. The combination with a form over 95 which a molded counter and the heel portion of a shoe in assembled relation thereto may be placed, said form having a marginal bead engageable with the counter outwardly of the stitch line between the sole and upper of the shoe, of a presser member engageable with the exposed heel end face of the shoe, 100 and spring elements positioned to wipe the upper over the counter as said member is being moved to clamping position, said member having an aperture through which 105 a fastener may be driven through the shoe sole and clinched on said form in position to fix the counter in position.

12. In a counter attaching device, a form 110 over which the molded counter and heel portion of a shoe may be placed, means including a clamping member engageable with the heel end face of the shoe and having a margin extending about the heel portion of the shoe for relatively centering the counter and shoe upper, and means for fixing the counter in position.

In testimony whereof I have affixed my signature.

MILTON L. DODGE.
